UNITED STATES PATENT OFFICE

REO P. WRIGHT, OF WASHINGTON, DISTRICT OF COLUMBIA, ASSIGNOR TO MARVEL CARBURETOR COMPANY, OF FLINT, MICHIGAN, A CORPORATION OF ILLINOIS

HEAT CONTROLLING MEANS FOR CHARGE FORMING DEVICES

Application filed August 15, 1929. Serial No. 386,126.

This invention relates to certain new and useful improvements in heat controlling means for charge forming devices and is a modification of my improved heat controlling means for charge forming devices disclosed in my application filed March 25, 1926, Serial Number 97,332, the object being to provide novel means for automatically controlling the application of heat to the charge forming device whereby the temperature of the charge can be regulated to a nicety in order to produce an explosive charge of high efficiency without any danger of overheating the charge throughout the entire range of operation of the engine under all atmospheric conditions.

Another object of my invention is to provide means for allowing the charge throttling valve to move a predetermined distance before the exhaust throttle valve is moved so as to allow the exhaust throttle valve to dwell on its seat while the throttle valve is moving into open position, whereby the exhaust gases will be held in the heating chamber so as to heat the charge quickly while the engine is warming up.

A further object of the invention is to provide a construction of heat control which is an improvement over the heat control employing a cam for varying the effect of movement of the charge throttling valve on the exhaust controlling valve by the use of a pressure chamber in communication with the cooling medium of the engine, which under normal conditions of the engine will hold the cam in its proper position in order that the application of heat will be controlled automatically to a nicety.

Other and further objects and advantages of the invention will be hereinafter set forth and the novel features thereof defined by the appended claims.

In the drawings,

Figure 1 is a side elevation of an internal combustion engine showing the application of my improved construction of pressure controlling means thereto, partly in section;

Figure 2 is an elevation on the opposite side to that shown in Figure 1 showing the cam and its manner of mounting and adjust-

ing the same by the pressure of the water of the cooling system;

Figure 3 is a vertical section through the manifold with the charge forming device detached;

Figure 4 is a detail view of the guide member and its connection with the throttle and main exhaust valves, and

Figure 5 is an enlarged side elevation of a heat controlling means for a charge forming device showing the application of the same to an internal combustion engine.

In the embodiment of my invention as herein shown 1 indicate an internal combustion engine, 2 an exhaust manifold, 3 the intake manifold and 4 a carbureter connected thereto having an air inlet 5 to which is connected a conduit 6 extending from an air heater 7 located around the exhaust, said conduit being provided with an additional valve controlled air inlet 8 for regulating the temperature of the heated air passing to the carbureter.

In the construction of carbureter as herein shown I provide the same with a heating jacket 9 having an inlet 10 which is disposed under an outlet 11 formed in the exhaust manifold 2 so that the exhaust gases from the exhaust manifold will circulate through the heating jacket 9 to heat the explosive charge produced by said carbureter and it is, of course, understood that the particular construction of heating jacket is not important so long as it is arranged to heat the explosive charge.

The inlet 10 of the heating jacket 9 of the charge forming device is provided with a volume valve 12 mounted on a stem 13 having an arm 14 for operating the same for controlling the volume of exhaust gases passing through the heating chamber and is adapted to be operated in conjunction with the controlling mechanism which will be herein described.

Arranged within the exhaust manifold 2 is an exhaust throttle valve 15 of the butterfly type carried by valve stem 16 provided with an arm 17 for operating the same, said valve being so constructed that when in closed position the exhaust passage will be completely closed in order to cause the entire

volume of exhaust gases to pass through the heating jacket.

Arranged on the end of the exhaust manifold is a coupling 18 having an exhaust pipe 19 connected thereto which extends in the usual manner to the muffler, not shown. The coupling 18 as herein shown is provided with an inlet nipple 20 from which extends a conduit 21 to an outlet nipple 22 formed on the heating jacket 9 of the carburetor whereby the exhaust gases will be by-passed around the exhaust throttling valve 15 when in closed position so that the exhaust gases will pass through the heating jacket in order to heat the explosive charge.

The carburetor is provided with a throttle valve 23 of the butterfly type carried by shaft 24 provided with an arm 25 to which is connected an operating rod 26 extending to the body of the automobile to which the device is attached so that it can be manipulated in the usual manner.

The object of this invention is to control the application of heat to a nicety by the use of pressure so that the temperature of the charge being formed by the carburetor will be controlled and in order to obtain this result I arrange on the shaft 24 of the throttle valve 23, a cam plate 27 which is movably mounted thereon so that it can be turned on the shaft, the position of the cam being controlled by a link 28 which is connected to a bell crank 29 to which is connected the movable wall of a pressure chamber A arranged in the engine water cooling system so that as the pressure in the cooling system increases and decreases, the cam plate will be adjusted as will be hereinafter fully described.

The pressure chamber A has an inlet B and an outlet C, the inlet B being in the nature of a pipe extending from the pump D which is provided with an inlet E in communication with the radiator of the automobile to which the internal combustion engine is used and the outlet C is connected through a suitable pipe to the water jacket of the internal combustion engine.

In the embodiment of the invention as herein shown, the movable wall is in the form of a piston F provided with a piston rod G which has its end connected to the lever 29 and is surrounded by a coil spring H which normally has the tendency to force the piston downwardly so that when the motor is stationary the cam will be in position to apply the full volume of heating medium to the heating chamber when the engine is first started, the spring being of such a strength that it resists the pressure of the cooling medium until a sufficient amount of pressure has been built up caused by the increased speed of the internal combustion engine to move the movable wall upwardly which adjusts the cam plate so as to vary the effect

of movement of the heat control in respect to the throttle valve.

While I have shown one embodiment of my invention, it is, of course, understood that my invention consists broadly in arranging a pressure chamber in a water cooling system of an internal combustion engine having the movable wall of the pressure chamber connected to means for adjusting the cam plate for obtaining the desired result and therefore I do not wish to limit myself to any particular means for accomplishing this result as I am aware that various changes can be made without departing from the spirit of my invention.

It is, of course, understood that the pump D for causing the cooling medium to circulate through the water circulating system is driven directly by the engine and therefore the speed of the pump is controlled by the speed of the engine so that when the engine is running slowly, the pressure in the pressure chamber is less than the pressure in the chamber when the engine is running at a high rate of speed and as the speed of the engine increases, the pressure increases so as to automatically adjust the cam plate.

The cam is connected to the arm 14 of the volume valve 13 by a link 32 so that as the cam is adjusted, the position of the valve 13 will be changed thereby increasing or decreasing the area of the exhaust inlet to the heating jacket and while in the drawing I have shown the volume valve arranged in the inlet to the heat jacket, it is, of course, understood that it can be arranged in the outlet without departing from the spirit of my invention.

In the construction of cam as herein shown, it is held in adjusted position by frictional means which comprises a pin 33 secured in the wall of the heat jacket and extending through a slot 34 formed in the cam plate 27, said pin carrying a frictional washer 35 engaging the outer face of the cam in such a manner that the cam is free to move and yet is held in adjusted position under normal conditions.

In the construction of cam plate as herein shown, a slot 37 is formed therein having at one end a substantially vertical portion and a substantially horizontal portion which gradually terminates in a downwardly extending portion. Slidably mounted within the slot of the cam plate is a member 38 provided with a roller having a guide flange for holding the same in the guideway formed by the slot so that it moves freely within the slot of the cam for the purpose hereinafter fully described.

The outer end of the member 38 is reduced as clearly shown on which is pivotally mounted a hub 39 having a socket 40 in which is secured an operating rod 41 which has its free end pivotally and adjustably connected to

the arm 17 of the exhaust gas throttling valve 15. The member 38 is preferably provided with a rigid arm 42 which is pivotally connected at its free end to a pin 44 pivotally mounted on the outer end of the arm 45 secured on one end of the throttle shaft 24 whereby the member 38 travels vertically in the vertical portion of the slot 37 of the cam plate when the throttle valve is oscillated so as to allow the throttle valve to move a predetermined distance before the movement of the arm carried thereby causes the arm of the exhaust throttle valve to move, whereby the exhaust throttling valve in the exhaust 15 pipe will dwell on its seat until the throttle valve has moved a predetermined distance so that the throttle valve is allowed to move a certain distance before operating the exhaust throttle valve and the further movement of the 20 throttle valve will cause the exhaust valve to open or move therewith, the movement of the exhaust valve in respect to the throttle valve being determined by the shape and position of the slot in the cam plate.

25 From the foregoing description it will be seen that I have provided an automatic heat controlling means for a charge forming device wherein the application of heat to the charge being produced is automatically controlled by the pressure of the water cooling system of the internal combustion engine through the medium of the cam which allows the throttle valve to move a predetermined distance before the exhaust throttling valve 30 starts to move so that the application of heat will be controlled to a nicety.

In the operation of the heat controlling means, the tendency of the spring behind the movable wall of the pressure chamber is to move the cam plate from the position shown in Figure 1, which position will allow the full volume of exhaust gases to pass to the heating chamber.

When the engine is started, the pump is rotated so as to cause the water to circulate through the cooling chamber and the pressure is built up in the pressure chamber so as to move the wall upwardly against the tension of the spring and as the movable wall moves upwardly, the lever 29 is rocked on its pivot and the cam plate adjusted so as to decrease the heating effect of the heating medium.

By constructing a heat controlling means in this manner, as the speed of the engine increases, the delivery of heating medium to the heating chamber is gradually decreased, whereby I am able to control the application of heat by the pressure of the cooling system, which in turn is controlled by the speed of the engine and thereby overcomes difficulties now existing in the manually operated means, as in some instances the operator fails to shift the position of the cam and the charge is overheated, while with my im-

proved construction of heat control, the cam is automatically adjusted by the speed of the engine.

What I claim is:

1. In a heat control for internal combustion engines having a forced feed water cooling system, the combination with valves arranged to throttle the exhaust gases and explosive charge, of means controlled by the pressure of the water cooling system of the internal combustion engine to vary the effect of movement of the charge controlling valve on the exhaust controlling valve. 70

2. The combination with an internal combustion engine having a forced feed water cooling system, of valves arranged to throttle the exhaust gases and explosive charge, means for connecting said valves, means for controlling the path of travel of said connecting means to vary the effect of movement of the charge controlling valve on the exhaust controlling valve and means controlled by the pressure of the water cooling system for adjusting said means. 80

3. The combination with an internal combustion engine having a forced feed water cooling system, of valves arranged to throttle the exhaust gases and explosive charge and means operated by the pressure of the water cooling system for adjusting said valves to vary the effect of movement of the charge controlling valve on the exhaust controlling valve. 90

4. In a heat control for internal combustion engines having a forced feed water cooling system, the combination with valves arranged to throttle the exhaust gases and explosive charge and means operated by the pressure of the water in the cooling system to vary the effect of movement of the charge controlling valve on the exhaust controlling valve. 100

5. In a heat control for internal combustion engines having a forced feed water cooling system, the combination with valves arranged to throttle the exhaust gases and explosive charge, means for connecting said valves and pressure controlled means for controlling the path of travel of said connecting means to vary the effect of movement of the charge controlling valve on the exhaust controlling valve. 110

6. The combination with an internal combustion engine having an exhaust passage, intake passage and charge forming device connected thereto, said internal combustion engine having a forced feed water cooling system, of a heater for heating the charge, a valve for controlling the passage of exhaust gases to said heater, a valve for controlling the passage of explosive charge to said engine, a volume valve controlling the volume of exhaust gases passing to said heater, a movable member for connecting said valves, and means controlled by the pressure of the 120

- water cooling system for controlling the path of travel of said movable member to vary the effect of movement of the charge controlling valve on the exhaust controlling valve.
7. The combination with an internal combustion engine having an exhaust passage, intake manifold and charge forming device connected thereto, having a throttle valve, said internal combustion engine being provided with a forced feed water cooling system, of a heater for heating the charge in its passage to the engine, a duct extending from said exhaust passage to said heater, an air heater arranged in the path of travel of said exhaust, a valve controlling the volume of exhaust gases passing through said heater and means controlled by the pressure in the water cooling system to adjust the position of said valves to vary the effect of the heat to the charge in said charge forming device.
- 10 8. The combination with an internal combustion engine having a forced feed water cooling system, of a heater for heating the charge delivered to the engine, a valve for controlling the passage of the heating medium to said heater, a valve for controlling the passage of explosive charge to said engine, and means controlled by the pressure of the water cooling system to vary the effect of movement of the charge controlling valve on the exhaust controlling valve.
- 15 9. The combination with an internal combustion engine having a forced feed water cooling system, means for heating the explosive charge in its passage to the internal combustion engine, means for controlling the passage of explosive charge to said engine, means for controlling the application of heat to said heating means, means connecting the last mentioned means to the means for controlling the passage of the charge to the engine, an adjustable member arranged to vary the volume of heating means in respect to the charge controlling means and means controlled by the pressure from the water cooling system for adjusting said adjustable member.
- 20 10. The combination with an internal combustion engine having an exhaust passage, intake passage and charge forming device connected thereto, of a heater arranged around the intake passage, means for bypassing exhaust gases through said heater, an air heater arranged around said by-pass, a valve for regulating the volume of exhaust gases passing through said heater, and means controlled by the pressure of the water in the water cooling system for adjusting said valve to vary the heating effect on the charge and the air delivered to said charge forming device.
- 25 11. The combination with an internal combustion engine having an exhaust passage, intake manifold and charge forming device connected thereto, said internal combustion engine having a forced feed water cooling system, of a heater for heating the charge in its passage to the engine, a valve for controlling the passage of exhaust gases to said heater, a valve for controlling the passage of explosive charge to said engine, a member having a connection with said valves, means arranged in the path of travel of said member to vary the effect of movement of the charge throttling valve on the exhaust throttling valve and means controlled by the pressure of the water in the water cooling system for adjusting said last mentioned means.
- 30 12. In a heat control for internal combustion engines having a forced feed water cooling system, the combination with means for throttling the exhaust gases and explosive charge, a member for connecting said means, a cam arranged in the path of travel of said connecting member, and means controlled by the pressure of the water in the water cooling system for adjusting said cam to vary the effect of movement of the charge controlling means on the exhaust controlling means.
- 35 13. The combination with an internal combustion engine having an exhaust passage, intake passage and charge forming device connected thereto, said engine having a forced feed water cooling system, of a heater for heating the charge in its passage to the engine, a valve for controlling the passage of exhaust gases to said heater, a valve for controlling the passage of explosive charge to said engine, a member having a connection with said valves, an adjustable member arranged in the path of travel of said member to vary the effect of movement of the charge controlling valve on the exhaust throttling valve and means controlled by the pressure of the water cooling system for adjusting said adjustable member.
- 40 14. In a heat control for internal combustion engines having a forced feed water cooling system, the combination with means for heating the explosive charge, means controlling the application of heat to said heating means, means controlling the passage of explosive charge to said engine, means for connecting said controlling means and pressure controlled means operated by the pressure of the water cooling system to vary the effect of movement of the charge controlling valve on the exhaust controlling valve.
- 45 15. The combination with an internal combustion engine having an exhaust passage, intake manifold and charge forming device connected thereto, said engine having a forced feed water cooling system, of a heater for heating the charge in its passage to said engine, a valve for throttling the passage of exhaust gases through said exhaust passage, means for conveying exhaust gases from said passage to said heater, a volume valve controlling the passage of exhaust gases from said heater, a throttle valve for said charge

forming device, a plate provided with a guideway disposed adjacent said charge forming device, a member mounted in said plate having a connection with said valves, and means operated by the pressure in the water cooling system for adjusting said plate to vary the effect of movement of the throttle valve on the exhaust throttling valve.

16. In a heat control for internal combustion engines having a forced feed water cooling system, means controlled by the position of the throttle valve controlling the application of heat for heating the charge in its passage to the engine and means for operating said last mentioned means controlled by the pressure of the water cooling system.

17. In a heat control for internal combustion engines having a forced feed water cooling system, the combination with valves arranged to throttle the exhaust gases and explosive charge, a member connecting said valves, a guide member for said connecting member, and means controlled by the pressure of the water cooling system of the internal combustion engine to adjust the position of said guide means to vary the effect of movement of the charge controlling valve on the exhaust controlling valve.

18. In a heat control for internal combustion engines having a forced feed water cooling system, the combination with valves arranged to throttle the exhaust gases and explosive charge, a member having a connection with said valves, a cam plate in which said member is adapted to travel and means controlled by the pressure of the water cooling system of the internal combustion engine for adjusting said cam plate to vary the effect of movement of the charge controlling valve on the exhaust controlling valve.

19. An internal combustion engine having a forced feed water cooling system, a heat controlling means for the charge forming device thereof, and means controlled by the pressure of the water in the cooling system for controlling the application of heat to said charge forming device.

In testimony whereof I hereunto affix my signature.

REA P. WRIGHT.
